UNITED STATES PATENT OFFICE.

ALBERT SCHMIDT, OF FLINT, MICHIGAN, ASSIGNOR TO CHAMPION IGNITION COMPANY,
OF FLINT, MICHIGAN, A CORPORATION OF MICHIGAN.

SPARK-PLUG.

1,241,561.

Specification of Letters Patent.

Patented Oct. 2, 1917.

Application filed January 18, 1917. Serial No. 143,149.

To all whom it may concern:

Be it known that I, ALBERT SCHMIDT, a citizen of the Republic of France, residing at Flint, in the county of Genesee and 5 State of Michigan, have invented certain new and useful Improvements, in Spark-Plugs, of which the following is a specification, reference being had therein to the accompanying drawings.

10 The invention relates to spark plugs and has more particular reference to the means employed for protecting the insulator from the combustion heat. To this end the invention consists in the construction as herein- 15 after set forth.

In the drawings:

Figure 1 is a longitudinal section through a spark-plug embodying my invention;

Fig. 2 is an inner end elevation thereof; 20 Fig. 2 is a cross-section on line $x-x$ Fig. 1.

In the present state of the art, it is common to form spark-plugs with insulators tapering at their inner ends and inclosed 25 in a casing having straight cylindrical walls. Where such constructions are used on high speed internal combustion engines, the flame which is forced into the cylindrical recess in contact with the tapering insulator will 30 rapidly heat the latter to a temperature where there is danger of preignition. With the present construction this defect is avoided by forming the inner end of the casing 35 of a shape corresponding to the tapering form of the insulator, so as to limit the volume of hot gas which can come into contact with the insulator surface. As specifically shown, A is the insulator having the enlarged portion B, with a shoulder C seated 40 on a gasket D on an opposed shoulder E of the casing F. The insulator is also provided with a tapering portion G beyond the shoulder C and extending to the inner end where the insulated electrode H is exposed. The 45 casing F is formed with a threaded nipple I engaging the water-jacketed engine casting, and the walls of this nipple portion are tapered corresponding to the taper of the portion G so as to leave a uniform space be- 50 tween the insulator and the surrounding case.

With the construction as described, during explosion the flame will be forced inward through the restricted annular space J

between the inner end of the insulator and 55 the casing and will travel inward until the compression is equal to the impelling force. Inasmuch, however, as the space between the insulator and the case is limited to the minimum required for proper insulation and to 60 prevent short circuiting by sooting, the amount of hot gas thus forced inward is considerably less than in a construction where there is a larger opening. Furthermore by reason of the tapering form the insulator 65 is constantly enlarging so as to provide an increasing cross-section for the conduction of the heat. Still further, the construction is one in which a relatively large gasket D may be used, which will conduct the heat 70 from the insulator to the surrounding case, while this gasket itself is protected from exposure to the flame by the contracting walls of the case surrounding the tapering portion of the insulator. Thus the amount of 75 heat which will be imparted to the insulator is reduced and provision is made for conducting away such heat as does enter.

What I claim as my invention is:

1. In a spark-plug, the combination with 80 an insulator having a tapering inner end, of a casing surrounding said insulator, having the recesses therein correspondingly tapered, said casing being slightly spaced from said insulator to leave a restricted an- 85 nular space.

2. In a spark-plug, the combination with 85 an insulator having a shouldered portion and a tapering inner end extending therefrom, of a casing having an opposed shoulder providing a seat for the shouldered portion of the insulator, said casing being also provided with a tapering recess surrounding and corresponding to the tapering portion of the insulator. 95

3. In a spark-plug, the combination with 100 an insulator having a tapering inner end portion and an enlargement providing a shoulder beyond said tapering portion, of a casing having a shoulder opposed to the shoulder on the insulator, a gasket forming a bearing and seal for the insulator on the casing, and said casing having a tapering recess surrounding and corresponding to the taper of the insulator, to restrict the 105 volume of space within the casing exposed to the flame.

4. In a spark-plug, a casing having a

shouldered portion and a threaded nipple, the nipple portion having a tapering recess therein, of an insulator seated on said shouldered portion and having a tapering inner end portion fitting within and uniformly spaced from the walls of said tapering recess, for the purpose described.

5. In a spark-plug, a casing having its nipple portion provided with a recess tapering from its outer end toward its inner end, 10 and an insulator within said tapering recess.

In testimony whereof I affix my signature.
ALBERT SCHMIDT.
